ABSTRACT

A system performs an optimization algorithm to optimize two or more acoustic sensors of a microphone array. The system obtains an array transfer function (ATF) for a plurality of combinations of the acoustic sensors of the microphone array. In a first embodiment, the algorithm optimizes an active set of acoustic sensors on the eyewear device. The plurality of combinations may be all possible combinations of subsets of the acoustic sensors that may be active. In a second embodiment, the algorithm optimizes a placement of two or more acoustic sensors on an eyewear device during manufacturing of the eyewear device. Each combination of acoustic sensors may represent a different arrangement of the acoustic sensors in the microphone array. In each embodiment, the system evaluates the obtained ATFs and, based on the evaluation, selects a combination of acoustic sensors for the microphone array.

**OPTIMIZATION OF MICROPHONE ARRAY
GEOMETRY FOR DIRECTION OF ARRIVAL
ESTIMATION**

BACKGROUND

The present disclosure generally relates to microphone arrays and specifically to optimization of microphone array geometries for direction of arrival estimation.

A sound perceived at two ears can be different, depending on a direction and a location of a sound source with respect to each ear as well as on the surroundings of a room in which the sound is perceived. Humans can determine a location of the sound source by comparing the sound perceived at each ear. In a “surround sound” system, a plurality of speakers reproduce the directional aspects of sound using acoustic transfer functions. An acoustic transfer function represents the relationship between a sound at its source location and how the sound is detected, for example, by a microphone array or by a person. A single microphone array (or a person wearing a microphone array) may have several associated acoustic transfer functions for several different source locations in a local area surrounding the microphone array (or surrounding the person wearing the microphone array). In addition, acoustic transfer functions for the microphone array may differ based on the position and/or orientation of the microphone array in the local area. Furthermore, the acoustic sensors of a microphone array can be arranged in a large number of possible combinations, and, as such, the associated acoustic transfer functions are unique to the microphone array. Determining an optimal set of acoustic sensors for each microphone array can require direct evaluation, which can be a lengthy and expensive process in terms of time and resources needed.

SUMMARY

Embodiments relate to a method for selecting a combination of acoustic sensors of a microphone array. The method may be performed during and/or prior to manufacturing of the microphone array to determine an optimal set of acoustic sensors in the microphone array. In some embodiments, at least some of the acoustic sensors of the microphone array are coupled to a near-eye display (NED). In one embodiment, a system obtains an array transfer function (ATF) for a plurality of combinations of acoustic sensors of the microphone array. An ATF characterizes how the microphone array receives a sound from a point in space. Each combination of acoustic sensors may be a subset of the acoustic sensors of the microphone array or may represent a different arrangement of the acoustic sensors in the microphone array. The system computes a Euclidean norm of each obtained ATF. The system computes an average of the Euclidean norms over a target source range and a target frequency range and then ranks each computed average. The system selects a combination of acoustic sensors for the microphone array based in part on the ranking. In some embodiments, the system activates the selected combination of acoustic sensors. In some embodiments, a computer-readable medium may be configured to perform the steps of the method.

In some embodiments, an audio system for selecting a combination of acoustic sensors of a microphone array is described. A microphone array monitors sounds in a local area surrounding the microphone array. The microphone array includes a plurality of acoustic sensors. At least some of the plurality of acoustic sensors are coupled to a near-eye

display (NED). The audio system also includes a controller that is configured to obtain an array transfer function (ATF) for a plurality of combinations of acoustic sensors of the microphone array. The controller computes a Euclidean norm of each obtained ATF. The controller computes an average of the Euclidean norms over a target source range and a target frequency range and then ranks each computed average. The controller selects a combination of acoustic sensors for the microphone array based in part on the ranking. In some embodiments, the controller activates the selected combination of acoustic sensors.

BRIEF DESCRIPTION OF THE DRAWINGS

15 Figure (FIG. 1 is an example illustrating an eyewear device including a microphone array, in accordance with one or more embodiments.

FIG. 2 is an example illustrating a portion of the eyewear device including an acoustic sensor that is a microphone on an ear of a user, in accordance with one or more embodiments.

20 FIG. 3 is an example illustrating an eyewear device including a neckband, in accordance with one or more embodiments.

FIG. 4 is a block diagram of an audio system, in accordance with one or more embodiments.

25 FIG. 5 is a flowchart illustrating a process of generating and updating a head-related transfer function of an eyewear device including an audio system, in accordance with one or more embodiments.

FIG. 6 is a flowchart illustrating a process of optimizing acoustic sensors on an eyewear device, in accordance with one or more embodiments.

30 FIG. 7 is a system environment of an eyewear device including an audio system, in accordance with one or more embodiments.

35 The figures depict embodiments of the present disclosure for purposes of illustration only. One skilled in the art will readily recognize from the following description that alternative embodiments of the structures and methods illustrated herein may be employed without departing from the principles, or benefits touted, of the disclosure described herein.

DETAILED DESCRIPTION

40 Microphone arrays are sometimes employed in spatial sound applications that require sound source localization and directional filtering. One of the major concerns of using microphone arrays is the choice of array geometry or, more generally, the problem of mutual microphone positioning to optimize certain acoustic characteristics of the array. Some 45 considerations for choosing parameters of a microphone array may include choosing the distance between adjacent sensors, the number of sensors, and the overall aperture of the array. In addition, some methods outline general differences between the spatial abilities of linear, planar, and volumetric array geometries. However, some methods may be limited when it comes to designing microphone arrays for specific applications. Direct evaluation of performance of a 50 large number of different possible microphone array geometries may be performed, but it is extremely expensive in terms of time and resource requirements.

55 A method for selecting a combination of acoustic sensors of a microphone array may be performed. The method may be performed during and/or prior to manufacturing of the microphone array or during use of the microphone array to determine an optimal set of acoustic sensors in the micro-

phone array. In some embodiments, prior to manufacturing of the microphone array, the optimal set of acoustic sensors may designate a set of parameters for placement of the acoustic sensors configured to be coupled to a near-eye display (NED). The set of parameters may include a number of acoustic sensors, a location of each acoustic sensor on the NED, an arrangement of the acoustic sensors, or some combination thereof. In some embodiments, the NED may be coupled with a neckband, on which some of the acoustic sensors of the microphone array may be located. After the microphone array is manufactured (e.g., coupled to the NED and/or neckband), the optimal set of acoustic sensors may designate a subset of the acoustic sensors that are active or inactive. In one embodiment, a system obtains an array transfer function (ATF) for a plurality of combinations of acoustic sensors of the microphone array. An ATF characterizes how the microphone array receives a sound from a point in space. Each combination of acoustic sensors may be a subset of the acoustic sensors of the microphone array or may represent a different arrangement of the acoustic sensors in the microphone array. The system computes a Euclidean norm of each obtained ATF. The system computes an average of the Euclidean norms over a target source range and a target frequency range and then ranks each computed average. The system selects a combination of acoustic sensors for the microphone array based in part on the ranking. In some embodiments, the system activates the selected combination of acoustic sensors. In some embodiments, a computer-readable medium may be configured to perform the steps of the method.

Embodiments of the present disclosure may include or be implemented in conjunction with an artificial reality system. Artificial reality is a form of reality that has been adjusted in some manner before presentation to a user, which may include, e.g., a virtual reality (VR), an augmented reality (AR), a mixed reality (MR), a hybrid reality, or some combination and/or derivatives thereof. Artificial reality content may include completely generated content or generated content combined with captured (e.g., real-world) content. The artificial reality content may include video, audio, haptic feedback, or some combination thereof, and any of which may be presented in a single channel or in multiple channels (such as stereo video that produces a three-dimensional effect to the viewer). Additionally, in some embodiments, artificial reality may also be associated with applications, products, accessories, services, or some combination thereof, that are used to, e.g., create content in an artificial reality and/or are otherwise used in (e.g., perform activities in) an artificial reality. The artificial reality system that provides the artificial reality content may be implemented on various platforms, including a head-mounted display (HMD) connected to a host computer system, a standalone HMD, a mobile device or computing system, or any other hardware platform capable of providing artificial reality content to one or more viewers.

Eyewear Device Configuration

FIG. 1 is an example illustrating an eyewear device 100 including an audio system, in accordance with one or more embodiments. The eyewear device 100 presents media to a user. In one embodiment, the eyewear device 100 may be a near-eye display (NED). Examples of media presented by the eyewear device 100 include one or more images, video, audio, or some combination thereof. The eyewear device 100 may include, among other components, a frame 105, a lens 110, a sensor device 115, and an audio system. The audio system may include, among other components, a microphone array of one or more acoustic sensors 120 and

a controller 125. While FIG. 1 illustrates the components of the eyewear device 100 in example locations on the eyewear device 100, the components may be located elsewhere on the eyewear device 100, on a peripheral device paired with the eyewear device 100, or some combination thereof.

The eyewear device 100 may correct or enhance the vision of a user, protect the eye of a user, or provide images to a user. The eyewear device 100 may be eyeglasses which correct for defects in a user's eyesight. The eyewear device 100 may be sunglasses which protect a user's eye from the sun. The eyewear device 100 may be safety glasses which protect a user's eye from impact. The eyewear device 100 may be a night vision device or infrared goggles to enhance a user's vision at night. The eyewear device 100 may be a near-eye display that produces VR, AR, or MR content for the user. Alternatively, the eyewear device 100 may not include a lens 110 and may be a frame 105 with an audio system that provides audio (e.g., music, radio, podcasts) to a user.

The frame 105 includes a front part that holds the lens 110 and end pieces to attach to the user. The front part of the frame 105 bridges the top of a nose of the user. The end pieces (e.g., temples) are portions of the frame 105 that hold the eyewear device 100 in place on a user (e.g., each end piece extends over a corresponding ear of the user). The length of the end piece may be adjustable to fit different users. The end piece may also include a portion that curls behind the ear of the user (e.g., temple tip, ear piece).

The lens 110 provides or transmits light to a user wearing the eyewear device 100. The lens 110 may be prescription lens (e.g., single vision, bifocal and trifocal, or progressive) to help correct for defects in a user's eyesight. The prescription lens transmits ambient light to the user wearing the eyewear device 100. The transmitted ambient light may be altered by the prescription lens to correct for defects in the user's eyesight. The lens 110 may be a polarized lens or a tinted lens to protect the user's eyes from the sun. The lens 110 may be one or more waveguides as part of a waveguide display in which image light is coupled through an end or edge of the waveguide to the eye of the user. The lens 110 may include an electronic display for providing image light and may also include an optics block for magnifying image light from the electronic display. Additional detail regarding the lens 110 is discussed with regards to FIG. 7. The lens 110 is held by a front part of the frame 105 of the eyewear device 100.

In some embodiments, the eyewear device 100 may include a depth camera assembly (DCA) that captures data describing depth information for a local area surrounding the eyewear device 100. In one embodiment, the DCA may include a structured light projector, an imaging device, and a controller. The captured data may be images captured by the imaging device of structured light projected onto the local area by the structured light projector. In one embodiment, the DCA may include two or more cameras that are oriented to capture portions of the local area in stereo and a controller. The captured data may be images captured by the two or more cameras of the local area in stereo. The controller computes the depth information of the local area using the captured data. Based on the depth information, the controller determines absolute positional information of the eyewear device 100 within the local area. The DCA may be integrated with the eyewear device 100 or may be positioned within the local area external to the eyewear device 100. In the latter embodiment, the controller of the DCA may transmit the depth information to the controller 125 of the eyewear device 100.

The sensor device 115 generates one or more measurement signals in response to motion of the eyewear device 100. The sensor device 115 may be located on a portion of the frame 105 of the eyewear device 100. The sensor device 115 may include a position sensor, an inertial measurement unit (IMU), or both. Some embodiments of the eyewear device 100 may or may not include the sensor device 115 or may include more than one sensor device 115. In embodiments in which the sensor device 115 includes an IMU, the IMU generates fast calibration data based on measurement signals from the sensor device 115. Examples of sensor devices 115 include: one or more accelerometers, one or more gyroscopes, one or more magnetometers, another suitable type of sensor that detects motion, a type of sensor used for error correction of the IMU, or some combination thereof. The sensor device 115 may be located external to the IMU, internal to the IMU, or some combination thereof.

Based on the one or more measurement signals, the sensor device 115 estimates a current position of the eyewear device 100 relative to an initial position of the eyewear device 100. The estimated position may include a location of the eyewear device 100 and/or an orientation of the eyewear device 100 or the user's head wearing the eyewear device 100, or some combination thereof. The orientation may correspond to a position of each ear relative to the reference point. In some embodiments, the sensor device 115 uses the depth information and/or the absolute positional information from a DCA to estimate the current position of the eyewear device 100. The sensor device 115 may include multiple accelerometers to measure translational motion (forward/back, up/down, left/right) and multiple gyroscopes to measure rotational motion (e.g., pitch, yaw, roll). In some embodiments, an IMU rapidly samples the measurement signals and calculates the estimated position of the eyewear device 100 from the sampled data. For example, the IMU integrates the measurement signals received from the accelerometers over time to estimate a velocity vector and integrates the velocity vector over time to determine an estimated position of a reference point on the eyewear device 100. Alternatively, the IMU provides the sampled measurement signals to the controller 125, which determines the fast calibration data. The reference point is a point that may be used to describe the position of the eyewear device 100. While the reference point may generally be defined as a point in space, however, in practice the reference point is defined as a point within the eyewear device 100.

The audio system detects sound to generate one or more acoustic transfer functions for a user. An acoustic transfer function characterizes how a sound is received from a point in space. The acoustic transfer functions may be array transfer functions (ATFs), head-related transfer functions (HRTFs), other types of acoustic transfer functions, or some combination thereof. The one or more acoustic transfer functions may be associated with the eyewear device 100, the user wearing the eyewear device 100, or both. The audio system may then use the one or more acoustic transfer functions to generate audio content for the user. The audio system of the eyewear device 100 includes a microphone array and the controller 125.

The microphone array detects sounds within a local area surrounding the microphone array. The microphone array includes a plurality of acoustic sensors. The acoustic sensors are sensors that detect air pressure variations induced by a sound wave. Each acoustic sensor is configured to detect sound and convert the detected sound into an electronic format (analog or digital). The acoustic sensors may be acoustic wave sensors, microphones, sound transducers, or

similar sensors that are suitable for detecting sounds. For example, in FIG. 1, the microphone array includes eight acoustic sensors: acoustic sensors 120a, 120b, which may be designed to be placed inside a corresponding ear of the user, and acoustic sensors 120c, 120d, 120e, 120f, 120g, 120h, which are positioned at various locations on the frame 105. The acoustic sensors 120a-120h may be collectively referred to herein as "acoustic sensors 120." Additional detail regarding the audio system is discussed with regards to FIG. 4.

The microphone array detects sounds within the local area surrounding the microphone array. The local area is the environment that surrounds the eyewear device 100. For example, the local area may be a room that a user wearing the eyewear device 100 is inside, or the user wearing the eyewear device 100 may be outside and the local area is an outside area in which the microphone array is able to detect sounds. Detected sounds may be uncontrolled sounds or controlled sounds. Uncontrolled sounds are sounds that are not controlled by the audio system and happen in the local area. Examples of uncontrolled sounds may be naturally occurring ambient noise. In this configuration, the audio system may be able to calibrate the eyewear device 100 using the uncontrolled sounds that are detected by the audio system. Controlled sounds are sounds that are controlled by the audio system. Examples of controlled sounds may be one or more signals output by an external system, such as a speaker, a speaker assembly, a calibration system, or some combination thereof. While the eyewear device 100 may be calibrated using uncontrolled sounds, in some embodiments, the external system may be used to calibrate the eyewear device 100 during a calibration process. Each detected sound (uncontrolled and controlled) may be associated with a frequency, an amplitude, a duration, or some combination thereof.

The configuration of the acoustic sensors 120 of the microphone array may vary. While the eyewear device 100 is shown in FIG. 1 as having eight acoustic sensors 120, the number of acoustic sensors 120 may be increased or decreased. Increasing the number of acoustic sensors 120 may increase the amount of audio information collected and the sensitivity and/or accuracy of the audio information. Decreasing the number of acoustic sensors 120 may decrease the computing power required by the controller 125 to process the collected audio information. In addition, the position of each acoustic sensor 120 of the microphone array may vary. The position of an acoustic sensor 120 may include a defined position on the user, a defined coordinate on the frame 105, an orientation associated with each acoustic sensor, or some combination thereof. For example, the acoustic sensors 120a, 120b may be positioned on a different part of the user's ear, such as behind the pinna or within the auricle or fossa, or there may be additional acoustic sensors on or surrounding the ear in addition to the acoustic sensors 120 inside the ear canal. Having an acoustic sensor (e.g., acoustic sensors 120a, 120b) positioned next to an ear canal of a user enables the microphone array to collect information on how sounds arrive at the ear canal. The acoustic sensors 120 on the frame 105 may be positioned along the length of the temples, across the bridge, above or below the lenses 110, or some combination thereof. The acoustic sensors 120 may be oriented such that the microphone array is able to detect sounds in a wide range of directions surrounding the user wearing the eyewear device 100. In some embodiments, an optimization process may be performed during the manufacturing of the eyewear device

100 to determine an optimal position of each acoustic sensor 120 in the microphone array, which is discussed in further detail with regards to FIG. 4.

The controller 125 processes information from the microphone array that describes sounds detected by the microphone array. The information associated with each detected sound may include a frequency, an amplitude, and/or a duration of the detected sound. For each detected sound, the controller 125 performs a DoA estimation. The DoA estimation is an estimated direction from which the detected sound arrived at an acoustic sensor of the microphone array. If a sound is detected by at least two acoustic sensors of the microphone array, the controller 125 can use the known positional relationship of the acoustic sensors and the DoA estimation from each acoustic sensor to estimate a source location of the detected sound, for example, via triangulation. The accuracy of the source location estimation may increase as the number of acoustic sensors that detected the sound increases and/or as the distance between the acoustic sensors that detected the sound increases.

In some embodiments, the controller 125 populates an audio data set with information. The information may include a detected sound and parameters associated with each detected sound. Example parameters may include a frequency, an amplitude, a duration, a DoA estimation, a source location, or some combination thereof. Each audio data set may correspond to a different source location relative to the NED and include one or more sounds having that source location. This audio data set may be associated with one or more acoustic transfer functions for that source location. The one or more acoustic transfer functions may be stored in the data set. In alternate embodiments, each audio data set may correspond to several source locations relative to the NED and include one or more sounds for each source location. For example, source locations that are located relatively near to each other may be grouped together. The controller 125 may populate the audio data set with information as sounds are detected by the microphone array. The controller 125 may further populate the audio data set for each detected sound as a DoA estimation is performed or a source location is determined for each detected sound.

In some embodiments, the controller 125 selects the detected sounds for which it performs a DoA estimation. The controller 125 may select the detected sounds based on the parameters associated with each detected sound stored in the audio data set. The controller 125 may evaluate the stored parameters associated with each detected sound and determine if one or more stored parameters meet a corresponding parameter condition. For example, a parameter condition may be met if a parameter is above or below a threshold value or falls within a target range. If a parameter condition is met, the controller 125 performs a DoA estimation for the detected sound. For example, the controller 125 may perform a DoA estimation for detected sounds that have a frequency within a frequency range, an amplitude above a threshold amplitude, a duration below a threshold duration, other similar variations, or some combination thereof. Parameter conditions may be set by a user of the audio system, based on historical data, based on an analysis of the information in the audio data set (e.g., evaluating the collected information of the parameter and setting an average), or some combination thereof. The controller 125 may create an element in the audio set to store the DoA estimation and/or source location of the detected sound. In some embodiments, the controller 125 may update the elements in the audio set if data is already present.

In some embodiments, the controller 125 may receive position information of the eyewear device 100 from a system external to the eyewear device 100. The position information may include a location of the eyewear device 100, an orientation of the eyewear device 100 or the user's head wearing the eyewear device 100, or some combination thereof. The position information may be defined relative to a reference point. The orientation may correspond to a position of each ear relative to the reference point. Examples of systems include an imaging assembly, a console (e.g., as described in FIG. 7), a simultaneous localization and mapping (SLAM) system, a depth camera assembly, a structured light system, or other suitable systems. In some embodiments, the eyewear device 100 may include sensors that may be used for SLAM calculations, which may be carried out in whole or in part by the controller 125. The controller 125 may receive position information from the system continuously or at random or specified intervals.

In one embodiment, based on parameters of the detected sounds, the controller 125 generates one or more acoustic transfer functions associated with the audio system. The transfer functions may be array transfer functions (ATFs), head-related transfer functions (HRTFs), other types of acoustic transfer functions, or some combination thereof. An ATF characterizes how the microphone array receives a sound from a point in space. Specifically, the ATF defines the relationship between parameters of a sound at its source location and the parameters at which the microphone array detected the sound. Parameters associated with the sound may include frequency, amplitude, duration, a DoA estimation, etc. In some embodiments, at least some of the acoustic sensors of the microphone array are coupled to an NED that is worn by a user. The ATF for a particular source location relative to the microphone array may differ from user to user due to a person's anatomy (e.g., ear shape, shoulders, etc.) that affects the sound as it travels to the person's ears. Accordingly, the ATFs of the microphone array are personalized for each user wearing the NED. Once the ATFs are generated, the ATFs may be stored in local or external memory.

The HRTF characterizes how an ear receives a sound from a point in space. The HRTF for a particular source location relative to a person is unique to each ear of the person (and is unique to the person) due to the person's anatomy (e.g., ear shape, shoulders, etc.) that affects the sound as it travels to the person's ears. For example, in FIG. 1, the controller 125 may generate two HRTFs for the user, one for each ear. An HRTF or a pair of HRTFs can be used to create audio content that includes sounds that seem to come from a specific point in space. Several HRTFs may be used to create surround sound audio content (e.g., for home entertainment systems, theater speaker systems, an immersive environment, etc.), where each HRTF or each pair of HRTFs corresponds to a different point in space such that audio content seems to come from several different points in space. In some embodiments, the controller 125 may update one or more pre-existing acoustic transfer functions based on the DoA estimation of each detected sound. The pre-existing acoustic transfer functions may be obtained from local or external memory or obtained from an external system. As the position of the eyewear device 100 changes within the local area, the controller 125 may generate a new acoustic transfer function or update a pre-existing acoustic transfer function accordingly. Once the HRTFs are generated, the HRTFs may be stored in local or external memory.

FIG. 2 is an example illustrating a portion of an eyewear device 200 including the acoustic sensor 120a that is a

microphone on an ear of a user, in accordance with one or more embodiments. The eyewear device 200 may be an embodiment of the eyewear device 100. The acoustic sensor 205 may be an embodiment of the acoustic sensor 120. As illustrated in FIG. 2, a portion of the eyewear device 200 is positioned behind the pinna to secure the eyewear device 200 to the user. The acoustic sensor 205 is positioned at an entrance of the ear of the user to detect pressure waves produced by sounds within the local area surrounding the user. Positioning an acoustic sensor 205 next to (or within) an ear canal of a user enables the acoustic sensor 205 to collect information on how sounds arrive at the ear canal such that a unique HRTF may be generated for each ear of the user.

FIG. 3 is an example illustrating an eyewear device 300 including a neckband 305, in accordance with one or more embodiments. In FIG. 3, the eyewear device 300 includes a frame 310, lenses 315, and an audio system. The eyewear device 300 may be an embodiment of the eyewear device 100. The audio system may be an embodiment of the audio system described with regards to FIG. 1. The audio system includes a microphone array, which includes several acoustic sensors, such as acoustic sensor 320a, which may be designed to be placed inside a corresponding ear of the user, and acoustic sensor 320b, which may be positioned along the frame 310. The audio system additionally includes a controller 325. The controller 325 may be an embodiment of the controller 125. The eyewear device 300 is coupled to the neckband 305 via a connector 330. While FIG. 3 illustrates the components of the eyewear device 300 and the neckband 305 in example locations on the eyewear device 300 and the neckband 305, the components may be located elsewhere and/or distributed differently on the eyewear device 300 and the neckband 305, on one or more additional peripheral devices paired with the eyewear device 300 and/or the neckband 305, or some combination thereof.

One way to allow eyewear devices to achieve the form factor of a pair of glasses, while still providing sufficient battery and computation power and allowing for expanded capabilities is to use a paired neckband. The power, computation and additional features may then be moved from the eyewear device to the neckband, thus reducing the weight, heat profile, and form factor of the eyewear device overall, while still retaining full functionality (e.g., AR, VR, and/or MR). The neckband allows components that would otherwise be included on the eyewear device to be heavier, since users may tolerate a heavier weight load on their shoulders than they would otherwise tolerate on their heads, due to a combination of soft-tissue and gravity loading limits. The neckband also has a larger surface area over which to diffuse and disperse generated heat to the ambient environment. Thus the neckband allows for greater battery and computation capacity than might otherwise have been possible simply on a stand-alone eyewear device. Since a neckband may be less invasive to a user than the eyewear device, the user may tolerate wearing the neckband for greater lengths of time than the eyewear device, allowing the artificial reality environment to be incorporated more fully into a user's day to day activities.

In the embodiment of FIG. 3, the neckband 305 is formed in a "U" shape that conforms to the user's neck. The neckband 305 is worn around a user's neck, while the eyewear device 300 is worn on the user's head. A first arm and a second arm of the neckband 305 may each rest on the top of a user's shoulders close to his or her neck such that the weight of the first arm and second arm are carried by the user's neck base and shoulders. The connector 330 is long

enough to allow the eyewear device 300 to be worn on a user's head while the neckband 305 rests around the user's neck. The connector 330 may be adjustable, allowing each user to customize the length of connector 330. The neckband 305 is communicatively coupled with the eyewear device 300. In some embodiments, the neckband 305 may be communicatively coupled to the eyewear device 300 and/or other devices. The other devices in the system may provide certain functions (e.g., tracking, localizing, depth mapping, processing, storage, etc.) to the eyewear device 300. In the embodiment of FIG. 3, the neckband 305 includes two acoustic sensors 320c, 320d of the microphone array, the controller 325, and a power source 335. The acoustic sensors 320 may be embodiments of the acoustic sensors 120.

The acoustic sensors 320c, 320d of the microphone array are positioned on the neckband 305. The acoustic sensors 320c, 320d may be embodiments of the acoustic sensor 120. The acoustic sensors 320c, 320d are configured to detect sound and convert the detected sound into an electronic format (analog or digital). The acoustic sensors may be acoustic wave sensors, microphones, sound transducers, or similar sensors that are suitable for detecting sounds. In the embodiment of FIG. 3, the acoustic sensors 320c, 320d are positioned on the neckband 305, thereby increasing the distance between the acoustic sensors 320c, 320d and the other acoustic sensors 320 positioned on the eyewear device 300. Increasing the distance between acoustic sensors 320 of the microphone array improve the accuracy of the microphone array. For example, if a sound is detected by acoustic sensors 320b and 320c, the distance between acoustic sensors 320b and 320c is greater than, e.g., the distance between acoustic sensors 320a and 320b, such that a determined source location of the detected sound may be more accurate than if the sound had been detected by acoustic sensors 320a and 320b.

The controller 325 processes information generated by the sensors on the eyewear device 300 and/or the neckband 305. The controller 325 may be an embodiment of the controller 125 and may perform some or all of the functions of the controller 125 described with regards to FIG. 1. The sensors on the eyewear device 300 may include the acoustic sensors 320, position sensors, an inertial measurement unit (IMU), other suitable sensors, or some combination thereof. For example, the controller 325 processes information from the microphone array that describes sounds detected by the microphone array. For each detected sound, the controller 325 may perform a DoA estimation to estimate a direction from which the detected sound arrived at the microphone array. As the microphone array detects sounds, the controller 325 may populate an audio data set with the information. In embodiments in which the eyewear device 300 includes an inertial measurement unit, the controller 325 may compute all inertial and spatial calculations from the IMU located on the eyewear device 300. The connector 330 may convey information between the eyewear device 300 and the neckband 305 and between the eyewear device 300 and the controller 325. The information may be in the form of optical data, electrical data, or any other transmittable data form. Moving the processing of information generated by the eyewear device 300 to the neckband 305 reduces the weight and heat generation of the eyewear device 300 making it more comfortable to the user.

The power source 335 provides power to the eyewear device 300 and the neckband 305. The power source 335 may be lithium ion batteries, lithium-polymer battery, primary lithium batteries, alkaline batteries, or any other form of power storage. Locating the power source 335 on the

neckband 305 may distribute the weight and heat generated by the power source 335 from the eyewear device 300 to the neckband 305, which may better diffuse and disperse heat, and also utilizes the carrying capacity of a user's neck base and shoulders. Locating the power source 335, controller 325 and any number of other sensors on the neckband device 305 may also better regulate the heat exposure of each of these elements, as positioning them next to a user's neck may protect them from solar and environmental heat sources.

Audio System Overview

FIG. 4 is a block diagram of an audio system 400, in accordance with one or more embodiments. The audio system in FIGS. 1 and 3 may be embodiments of the audio system 400. In the embodiment of FIG. 4, the audio system 400 detects sound to generate one or more acoustic transfer functions for a user. In some embodiments, the audio system 400 may obtain one or more pre-existing acoustic transfer functions from local or external memory or an external system. The audio system 400 may then use the one or more acoustic transfer functions to generate audio content for the user. In the embodiment of FIG. 4, the audio system 400 includes a microphone array 405, a controller 410, and a speaker assembly 415. Some embodiments of the audio system 400 have different components than those described here. Similarly, in some cases, functions can be distributed among the components in a different manner than is described here.

The microphone array 405 detects sounds within a local area surrounding the microphone array. The microphone array 405 may include a plurality of acoustic sensors that each detect air pressure variations due to a sound wave and convert the detected sounds into an electronic format (analog or digital). The plurality of acoustic sensors may be positioned on an eyewear device (e.g., eyewear device 100), on a user (e.g., in an ear canal of the user), on a neckband, or some combination thereof. As described with regards to FIG. 1, detected sounds may be uncontrolled sounds or controlled sounds. Each detected sound may be associated with audio information such as a frequency, an amplitude, a duration, or some combination thereof. Each acoustic sensor of the microphone array 405 may be active (powered on) or inactive (powered off). The acoustic sensors are activated or deactivated in accordance with instructions from the controller 410. In some embodiments, all of the acoustic sensors in the microphone array 405 may be active to detect sounds, or a subset of the plurality of acoustic sensors may be active. An active subset includes at least two acoustic sensors of the plurality of acoustic sensors. An active subset may include, e.g., every other acoustic sensor, a pre-programmed initial subset, a random subset, or some combination thereof.

The controller 410 processes information from the microphone array 405. In addition, the controller 410 controls other modules and devices of the audio system 400. The information associated with each detected sound may include a frequency, an amplitude, and/or a duration of the detected sound. In the embodiment of FIG. 4, the controller 410 includes the DoA estimation module 420, the transfer function module 425, and the array optimization module 430.

The DoA estimation module 420 performs a DoA estimation for detected sounds. DoA estimation is an estimated direction from which a detected sound arrived at an acoustic sensor of the microphone array 405. If a sound is detected by at least two acoustic sensors of the microphone array, the controller 125 can use the positional relationship of the acoustic sensors and the DoA estimation from each acoustic

sensor to estimate a source location of the detected sound, for example, via triangulation. The DoA estimation of each detected sound may be represented as a vector between an estimated source location of the detected sound and the position of the microphone array 405 within the local area. The estimated source location may be a relative position of the source location in the local area relative to a position of the microphone array 405. The position of the microphone array 405 may be determined by one or more sensors on an 10 eyewear device and/or neckband having the microphone array 405. In some embodiments, the controller 410 may determine an absolute position of the source location if an absolute position of the microphone array 405 is known in the local area. The position of the microphone array 405 may 15 be received from an external system (e.g., an imaging assembly, an AR or VR console, a SLAM system, a depth camera assembly, a structured light system etc.). The external system may create a virtual model of the local area, in which the local area and the position of the microphone 20 array 405 are mapped. The received position information may include a location and/or an orientation of the microphone array in the mapped local area. The controller 410 may update the mapping of the local area with determined 25 source locations of detected sounds. The controller 125 may receive position information from the external system continuously or at random or specified intervals. In some embodiments, the controller 410 selects the detected sounds for which it performs a DoA estimation.

The DoA estimation module 420 selects the detected 30 sounds for which it performs a DoA estimation. As described with regards to FIG. 1, the DoA estimation module 420 populates an audio data set with information. The information may include a detected sound and parameters associated with each detected sound. Example parameters may include 35 a frequency, an amplitude, a duration, a DoA estimation, a source location, or some combination thereof. Each audio data set may correspond to a different source location relative to the microphone array 405 and include one or more sounds having that source location. The DoA estimation module 420 may populate the audio data set as sounds 40 are detected by the microphone array 405. The DoA estimation module 420 may evaluate the stored parameters associated with each detected sound and determine if one or more stored parameters meet a corresponding parameter 45 condition. For example, a parameter condition may be met if a parameter is above or below a threshold value or falls within a target range. If a parameter condition is met, the DoA estimation module 420 performs a DoA estimation for the detected sound. For example, the DoA estimation module 420 may perform a DoA estimation for detected sounds that have a frequency within a frequency range, an amplitude above a threshold amplitude, a duration below a threshold duration range, other similar variations or some combination thereof. Parameter conditions may be set by a user of 50 the audio system 400, based on historical data, based on an analysis of the information in the audio data set (e.g., evaluating the collected information for a parameter and setting an average), or some combination thereof. The DoA estimation module 420 may further populate or update the 55 audio data set as it performs DoA estimations for detected sounds.

The transfer function module 425 generates one or more 60 acoustic transfer functions associated with the source locations of sounds detected by the microphone array 405. Generally, an acoustic transfer function is a mathematical function giving a corresponding output value for each possible input value. In the embodiment of FIG. 4, an acoustic

transfer function represents the relationship between a sound at its source location and how the sound is detected, for example, by a microphone array or by a person. Each acoustic transfer function may be associated with a position (i.e., location and/or orientation) of the microphone array or person and may be unique to that position. For example, as the location and/or orientation of the microphone array or head of the person changes, sounds may be detected differently in terms of frequency, amplitude, etc. In the embodiment of FIG. 4, the transfer function module 425 uses the information in the audio data set to generate the one or more acoustic transfer functions. The information may include a detected sound and parameters associated with each detected sound. Example parameters may include a frequency, an amplitude, a duration, a DoA estimation, a source location, or some combination thereof. The DoA estimations from the DoA estimation module 420 may improve the accuracy of the acoustic transfer functions. The acoustic transfer functions may be used for various purposes discussed in greater detail below. In some embodiments, the transfer function module 425 may update one or more pre-existing acoustic transfer functions based on the DoA estimations of the detected sounds. As the position (i.e., location and/or orientation) of the microphone array 405 changes within the local area, the controller 410 may generate a new acoustic transfer function or update a pre-existing acoustic transfer function accordingly associated with each position.

In one embodiment, the transfer function module 425 generates an array transfer function (ATF). The ATF characterizes how the microphone array 405 receives a sound from a point in space. Specifically, the ATF defines the relationship between parameters of a sound at its source location and the parameters at which the microphone array 405 detected the sound. Parameters associated with the sound may include frequency, amplitude, duration, etc. The transfer function module 425 may generate one or more ATFs for a particular source location of a detected sound, a position of the microphone array 405 in the local area, or some combination thereof. Factors that may affect how the sound is received by the microphone array 405 may include the arrangement and/or orientation of the acoustic sensors in the microphone array 405, any objects in between the sound source and the microphone array 405, an anatomy of a user wearing the eyewear device with the microphone array 405, or other objects in the local area. For example, if a user is wearing an eyewear device that includes the microphone array 405, the anatomy of the person (e.g., ear shape, shoulders, etc.) may affect the sound waves as it travels to the microphone array 405. In another example, if the user is wearing an eyewear device that includes the microphone array 405 and the local area surrounding the microphone array 405 is an outside environment including buildings, trees, bushes, a body of water, etc., those objects may dampen or amplify the amplitude of sounds in the local area. Generating and/or updating an ATF improves the accuracy of the audio information captured by the microphone array 405.

In one embodiment, the transfer function module 425 generates one or more HRTFs. An HRTF characterizes how an ear of a person receives a sound from a point in space. The HRTF for a particular source location relative to a person is unique to each ear of the person (and is unique to the person) due to the person's anatomy (e.g., ear shape, shoulders, etc.) that affects the sound as it travels to the person's ears. The transfer function module 425 may generate a plurality of HRTFs for a single person, where each HRTF may be associated with a different source location, a

different position of the person wearing the microphone array 405, or some combination thereof. In addition, for each source location and/or position of the person, the transfer function module 425 may generate two HRTFs, one for each ear of the person. As an example, the transfer generation module 425 may generate two HRTFs for a user at a particular location and orientation of the user's head in the local area relative to a single source location. If the user turns his or her head in a different direction, the transfer generation module 425 may generate two new HRTFs for the user at the particular location and the new orientation, or the transfer generation module 425 may update the two pre-existing HRTFs. Accordingly, the transfer function module 425 generates several HRTFs for different source locations, different positions of the microphone array 405 in a local area, or some combination thereof.

In one embodiment, the transfer function module 425 obtains one or more pre-existing acoustic transfer functions from local or external memory or from an external system. The acoustic transfer functions may be ATFs, HRTFs, other types of acoustic transfer functions, or some combination thereof. The pre-existing acoustic transfer functions may be obtained by various methods. One method may include premeasuring acoustic transfer functions using a generic human model or an acoustic dummy. One method may include modeling the acoustic transfer functions using known theoretical solutions of sound propagation in a test field or around simple geometric structures. One method may include using a combination of the previously described methods.

In some embodiments, the transfer function module 425 may use the plurality of HRTFs and/or ATFs for a user to generate audio content for the user. The transfer function module 425 may generate an audio characterization configuration that can be used by the speaker assembly 415 for generating sounds (e.g., stereo sounds or surround sounds). The audio characterization configuration is a function, which the audio system 400 may use to synthesize a binaural sound that seems to come from a particular point in space. Accordingly, an audio characterization configuration specific to the user allows the audio system 400 to provide sounds and/or surround sound to the user. The audio system 400 may use the speaker assembly 415 to provide the sounds. In some embodiments, the audio system 400 may use the microphone array 405 in conjunction with or instead of the speaker assembly 415. In one embodiment, the plurality of ATFs, plurality of HRTFs, and/or the audio characterization configuration are stored on the controller 410.

The array optimization module 430 optimizes the active set of acoustic sensors in the microphone array 405. In FIG. 4, all or a subset of the acoustic sensors in the microphone array 405 may be active to detect sounds. In some embodiments, the array optimization module 430 determines which acoustic sensors are to be active based on parameters associated with sounds detected by the microphone array 405 stored in the audio data set. As previously described, each detected sound may be associated with a frequency, an amplitude, a duration, a source location, or some combination thereof. The array optimization module 430 may evaluate one or more parameters associated with detected sounds stored in the audio data set. The array optimization module 430 determines if one or more of the parameters meets a parameter condition. For example, a parameter condition may be met if a parameter is above or below a threshold value or falls within a target range associated with each parameter. In response to determining that one or more

parameters meet a parameter condition, the array optimization module 430 may activate particular acoustic sensors in the microphone array 405. In some embodiments, the array optimization module 430 may also deactivate particular acoustic sensors in the microphone array 405. For example, the array optimization module 430 may select a subset of acoustic sensors based on a direction from which one or more detected sounds were received such that acoustic sensors that are oriented in that direction are active to best detect additional sounds from that direction. Further to the example, the array optimization module 430 may deactivate the remaining acoustic sensors in the microphone array 405 (e.g., acoustic sensors that are oriented in an opposite direction). In some embodiments, the array optimization module 430 may be programmed to evaluate detected sounds within the local area continuously or at random or specified intervals to determine an optimal set of active acoustic sensors. In some embodiments, the array optimization module 430 may select a subset of acoustic sensors based on a direction from which a detected sound is received such that acoustic sensors that are oriented in that direction are active to best detect additional sounds from that direction.

In one embodiment, the array optimization module 430 performs an optimization algorithm to determine an optimal active set of acoustic sensors in the microphone array 405. Since the microphone array 405 includes a plurality of acoustic sensors, there are several possible combinations for subsets of the acoustic sensors that may be active. The array optimization module 430 may evaluate an ATF for each of the possible combinations and, based on the evaluation, select the combination of acoustic sensors. The array optimization module 430 may then activate or deactivate acoustic sensors based on the selected combination. For example, if an acoustic sensor is part of the selected combination and is already active, then the acoustic sensor remains active. If an acoustic sensor is not part of the selected combination and is not active, then the acoustic sensor remains inactive. If an acoustic sensor is part of the selected combination and is not active, then the acoustic sensor becomes active (and vice versa). The optimization algorithm is further discussed with regards to FIG. 6.

In one embodiment, the optimization algorithm may be performed during and/or prior to manufacturing of the microphone array 405. An external workstation may be configured to perform the optimization algorithm to determine an optimal physical location and physical orientation of the acoustic sensors, of the microphone array 405, that are to be coupled to a device (e.g., an eyewear device and/or a neckband). In this embodiment, each combination of acoustic sensors may represent a different arrangement of the acoustic sensors in the microphone array. An arrangement may indicate the location and/or orientation of the acoustic sensor on a device to which the microphone array 405 may be coupled. In some embodiments, the console may be configured to receive a plurality of input parameters, such as a type of device that the microphone array is to be coupled to, the dimensions and/or configuration of the device, an environment in which the microphone array is going to be used, or some combination thereof. Based on the input parameters, the workstation may output a microphone array design. The microphone array design may specify a number of acoustic sensors that the microphone array is to include, the location of each acoustic sensor on the device, and/or an orientation of each acoustic sensor on the device, among other specifications.

The speaker assembly 415 is configured to transmit sound to a user. The speaker assembly 415 may operate according to commands from the controller 410 and/or based on an audio characterization configuration from the controller 410. 5 Based on the audio characterization configuration, the speaker assembly 415 may produce binaural sounds that seem to come from a particular point in space. The speaker assembly 415 may provide a sequence of sounds or surround sound to the user. In some embodiments, the speaker assembly 415 and the microphone array 415 may be used together to provide sides to the user. The speaker assembly 415 may be coupled to an NED to which the microphone array 405 is coupled. In alternate embodiments, the speaker assembly 415 may be a plurality of speakers surrounding a user 10 wearing the microphone array 405 (e.g., coupled to an NED). In one embodiment, the speaker assembly 415 transmits test sounds during a calibration process of the microphone array 405. The controller 410 may instruct the speaker assembly 415 to produce test sounds and then may analyze 15 the test sounds received by the microphone array 405 to generate acoustic transfer functions for the eyewear device 100. Multiple test sounds with varying frequencies, amplitudes, durations, or sequences can be produced by the speaker assembly 415.

25 Head-Related Transfer Function (HRTF) Personalization

FIG. 5 is a flowchart illustrating a process 500 of updating a head-related transfer function of an eyewear device (e.g., eyewear device 100) including an audio system (e.g., audio system 400), in accordance with one or more embodiments. 30 In one embodiment, the process of FIG. 5 is performed by components of the audio system. Other entities may perform some or all of the steps of the process in other embodiments (e.g., a console). Likewise, embodiments may include different and/or additional steps, or perform the steps in different orders.

The audio system monitors 510 sounds in a local area surrounding a microphone array on the eyewear device. The microphone array may detect sounds such as uncontrolled sounds and controlled sounds that occur in the local area. 40 Each detected sound may be associated with a frequency, an amplitude, a duration, or some combination thereof. In some embodiments, the audio system stores the information associated with each detected sound in an audio data set.

In some embodiments, the audio system optionally estimates 45 520 a position of the microphone array in the local area. The estimated position may include a location of the microphone array and/or an orientation of the eyewear device or a user's head wearing the eyewear device, or some combination thereof. In one embodiment, the audio system may include one or more sensors that generate one or more measurement signals in response to motion of the microphone array. The audio system may estimate 510 a current position of the microphone array relative to an initial position of the microphone array. In another embodiment, the 55 audio system may receive position information of the eyewear device from an external system (e.g., an imaging assembly, an AR or VR console, a SLAM system, a depth camera assembly, a structured light system, etc.).

The audio system performs 530 a Direction of Arrival (DoA) estimation for each detected sound relative to the 60 position of the microphone array. The DoA estimation is an estimated direction from which the detected sound arrived at an acoustic sensor of the microphone array. The DoA estimation may be represented as a vector between an estimated source location of the detected sound and the position of the eyewear device within the local area. In some 65 embodiments, the audio system may perform 530 a DoA

estimation for detected sounds associated with a parameter that meets a parameter condition. For example, a parameter condition may be met if a parameter is above or below a threshold value or falls within a target range.

The audio system updates 540 one or more acoustic transfer functions. The acoustic transfer function may be an array transfer function (ATF) or a head-related transfer function (HRTF). An acoustic transfer function represents the relationship between a sound at its source location and how the sound is detected. Accordingly, each acoustic transfer function is associated with a different source location of a detected sound, a different position of a microphone array, or some combination thereof. As a result, the audio system may update 540 a plurality of acoustic transfer functions for a particular source location and/or position of the microphone array in the local area. In some embodiments, the eyewear device may update 540 two HRTFs, one for each ear of a user, for a particular position of the microphone array in the local area. In some embodiments, the audio system generates one or more acoustic transfer functions that are each associated with a different source location of a detected sound, a different position of a microphone array, or some combination thereof.

If the position of the microphone array changes within the local area, the audio system may generate one or more new acoustic transfer functions or update 540 one or more pre-existing acoustic transfer functions accordingly. The process 500 may be continuously repeated as a user wearing the microphone array (e.g., coupled to an NED) moves through the local area, or the process 500 may be initiated upon detecting sounds via the microphone array.

Microphone Array Optimization

FIG. 6 is a flowchart illustrating a process 600 of optimizing acoustic sensors on an eyewear device, in accordance with one or more embodiments. In a first embodiment, the process 600 of FIG. 6 is performed by an audio system (e.g., the audio system 400) to optimize an active set of acoustic sensors on the eyewear device. Since the microphone array includes a plurality of acoustic sensors, there are several possible combinations for subsets of the acoustic sensors that may be active. In a second embodiment, the process 600 of FIG. 6 is performed by an audio system, or components thereof (e.g., a controller) operating on an external workstation to optimize placement of a plurality of acoustic sensors on an eyewear device prior to and/or during manufacturing of the eyewear device. In this embodiment, each combination of acoustic sensors may represent a different arrangement of the acoustic sensors in the microphone array. Other entities may perform some or all of the steps of the process in other embodiments. Likewise, embodiments may include different and/or additional steps, or perform the steps in different orders.

The audio system obtains 610 an array transfer function (ATF) for each of a plurality of combinations of acoustic sensors in a microphone array on the eyewear device. The array transfer functions may be obtained from local or external memory or obtained from a system external to the audio system. In the first embodiment, the plurality of combinations may include all possible combinations of subsets of acoustic sensors that could be active (including the full set of acoustic sensors). In the second embodiment, the plurality of combinations may include all possible arrangements of the acoustic sensors of the microphone array on the eyewear device. An arrangement may indicate the number, location, and/or orientation of the acoustic sensors on the eyewear device.

The audio system computes 620 the Euclidean norm of each obtained ATF. A Euclidean norm is a length of a vector (i.e., a magnitude). In the embodiment of FIG. 6, an ATF may be in the form of a vector, such that the audio system computes its magnitude. The Euclidean norm may be computed 620 using Equation (1).

$$\|v(\omega, \theta)\|_2 = \sqrt{v(\omega, \theta)^H \cdot v(\omega, \theta)} \quad (1),$$

where $v(\omega, \theta)$ is a column vector defining the ATF at frequency ω and direction θ .

The audio system computes 630 an average of the Euclidean norms over a target source range and frequency range. The average may be computed 630 using Equation (2).

$$\frac{1}{N} \sum_{\theta} \sum_{\omega} \|v(\omega, \theta)\|_2, \quad (2)$$

where N is the total number of elements in the summation, ω is frequency, and θ is direction.

The target source range may comprise a range of directions of a source location relative to the audio system. The frequency range may be a range of frequencies of sounds detected by the microphone array. In the first embodiment, the audio system may select a target source range and a target frequency range based on an initial DoA estimation using an initial set of active acoustic sensors in the microphone array on the eyewear device. In some embodiments, the computed average may be weighted based on a variety of parameters. The weights of each individual frequency and/or arrival direction may be computed based on their relative importance.

The audio system ranks 640 the computed averages. The audio system may rank 640 the computed averages in order of highest to lowest, or vice versa. A high average may correspond to high signal-to-noise (SNR) ratio and, therefore, better overall performance. A low average may correspond to a low SNR ratio and reduced performance.

The audio system selects 650 a combination of acoustic sensors for the microphone array based in part on the ranking. For example, the audio system may select 650 the combination with a highest average norm. In the first embodiment, the audio system sets the selected combination of acoustic sensors to active such that the selected combination can detect sounds. In the first embodiment, the audio system may refine its initial DoA estimation using the newly-selected active set of acoustic sensors.

In the second embodiment, where the process 600 of FIG. 6 is performed during manufacturing of the audio system, each combination of acoustic sensors represents a different arrangement of the acoustic sensors in the microphone array. Accordingly, the acoustic sensors may be coupled to an eyewear device in the arrangement determined by the selected combination.

Example System Environment

FIG. 7 is a system environment 700 of an eyewear device 705 including an audio system, in accordance with one or more embodiments. The system 700 may operate in an artificial reality environment. The system 700 shown in FIG. 7 includes an eyewear device 705 and an input/output (I/O) interface 710 that is coupled to a console 715. The eyewear device 705 may be an embodiment of the eyewear device 100. While FIG. 7 shows an example system 700 including one eyewear device 705 and one I/O interface 710, in other embodiments any number of these components may be included in the system 700. For example, there may be

multiple eyewear devices 705 each having an associated I/O interface 710 with each eyewear device 705 and I/O interface 710 communicating with the console 715. In alternative configurations, different and/or additional components may be included in the system 700. Additionally, functionality described in conjunction with one or more of the components shown in FIG. 7 may be distributed among the components in a different manner than described in conjunction with FIG. 7 in some embodiments. For example, some or all of the functionality of the console 715 is provided by the eyewear device 705.

In some embodiments, the eyewear device 705 may correct or enhance the vision of a user, protect the eye of a user, or provide images to a user. The eyewear device 705 may be eyeglasses which correct for defects in a user's eyesight. The eyewear device 705 may be sunglasses which protect a user's eye from the sun. The eyewear device 705 may be safety glasses which protect a user's eye from impact. The eyewear device 705 may be a night vision device or infrared goggles to enhance a user's vision at night. Alternatively, the eyewear device 705 may not include lenses and may be just a frame with an audio system 720 that provides audio (e.g., music, radio, podcasts) to a user.

In some embodiments, the eyewear device 705 may be a head-mounted display that presents content to a user comprising augmented views of a physical, real-world environment with computer-generated elements (e.g., two dimensional (2D) or three dimensional (3D) images, 2D or 3D video, sound, etc.). In some embodiments, the presented content includes audio that is presented via an audio system 720 that receives audio information from the eyewear device 705, the console 715, or both, and presents audio data based on the audio information. In some embodiments, the eyewear device 705 presents virtual content to the user that is based in part on a real environment surrounding the user. For example, virtual content may be presented to a user of the eyewear device. The user physically may be in a room, and virtual walls and a virtual floor of the room are rendered as part of the virtual content. In the embodiment of FIG. 7, the eyewear device 705 includes an audio system 720, an electronic display 725, an optics block 730, a position sensor 735, a depth camera assembly (DCA) 740, and an inertial measurement (IMU) unit 745. Some embodiments of the eyewear device 705 have different components than those described in conjunction with FIG. 7. Additionally, the functionality provided by various components described in conjunction with FIG. 7 may be distributed differently among the components of the eyewear device 705 in other embodiments or be captured in separate assemblies remote from the eyewear device 705.

The audio system 720 detects sound to generate or update one or more acoustic transfer functions for a user. The audio system 720 may then use the one or more acoustic transfer functions to generate audio content for the user. The audio system 720 may be an embodiment of the audio system 400. As described with regards to FIG. 4, the audio system 720 may include a microphone array, a controller, and a speaker assembly, among other components. The microphone array detects sounds within a local area surrounding the microphone array. The microphone array may include a plurality of acoustic sensors that each detect air pressure variations of a sound wave and convert the detected sounds into an electronic format (analog or digital). The plurality of acoustic sensors may be positioned on an eyewear device (e.g., eyewear device 100), on a user (e.g., in an ear canal of the user), on a neckband, or some combination thereof. Detected sounds may be uncontrolled sounds or controlled sounds.

The controller performs a DoA estimation for the sounds detected by the microphone array. Based in part on the DoA estimations of the detected sounds and parameters associated with the detected sounds, the controller generates one or more acoustic transfer functions associated with the source locations of the detected sounds. The acoustic transfer functions may be ATFs, HRTFs, other types of acoustic transfer functions, or some combination thereof. The controller may generate instructions for the speaker assembly to emit audio content that seems to come from several different points in space.

The electronic display 725 displays 2D or 3D images to the user in accordance with data received from the console 715. In various embodiments, the electronic display 725 comprises a single electronic display or multiple electronic displays (e.g., a display for each eye of a user). Examples of the electronic display 725 include: a liquid crystal display (LCD), an organic light emitting diode (OLED) display, an active-matrix organic light-emitting diode display (AMOLED), some other display, or some combination thereof.

The optics block 730 magnifies image light received from the electronic display 725, corrects optical errors associated with the image light, and presents the corrected image light to a user of the eyewear device 705. The electronic display 725 and the optics block 730 may be an embodiment of the lens 110. In various embodiments, the optics block 730 includes one or more optical elements. Example optical elements included in the optics block 730 include: an aperture, a Fresnel lens, a convex lens, a concave lens, a filter, a reflecting surface, or any other suitable optical element that affects image light. Moreover, the optics block 730 may include combinations of different optical elements. In some embodiments, one or more of the optical elements in the optics block 730 may have one or more coatings, such as partially reflective or anti-reflective coatings.

Magnification and focusing of the image light by the optics block 730 allows the electronic display 725 to be physically smaller, weigh less, and consume less power than larger displays. Additionally, magnification may increase the field of view of the content presented by the electronic display 725. For example, the field of view of the displayed content is such that the displayed content is presented using almost all (e.g., approximately 110 degrees diagonal), and in some cases all, of the user's field of view. Additionally in some embodiments, the amount of magnification may be adjusted by adding or removing optical elements.

In some embodiments, the optics block 730 may be designed to correct one or more types of optical error. Examples of optical error include barrel or pincushion distortion, longitudinal chromatic aberrations, or transverse chromatic aberrations. Other types of optical errors may further include spherical aberrations, chromatic aberrations, or errors due to the lens field curvature, astigmatisms, or any other type of optical error. In some embodiments, content provided to the electronic display 725 for display is pre-distorted, and the optics block 730 corrects the distortion when it receives image light from the electronic display 725 generated based on the content.

The DCA 740 captures data describing depth information for a local area surrounding the eyewear device 705. In one embodiment, the DCA 740 may include a structured light projector, an imaging device, and a controller. The captured data may be images captured by the imaging device of structured light projected onto the local area by the structured light projector. In one embodiment, the DCA 740 may include two or more cameras that are oriented to capture portions of the local area in stereo and a controller. The

captured data may be images captured by the two or more cameras of the local area in stereo. The controller computes the depth information of the local area using the captured data. Based on the depth information, the controller determines absolute positional information of the eyewear device 705 within the local area. The DCA 740 may be integrated with the eyewear device 705 or may be positioned within the local area external to the eyewear device 705. In the latter embodiment, the controller of the DCA 740 may transmit the depth information to a controller of the audio system 720.

The IMU 745 is an electronic device that generates data indicating a position of the eyewear device 705 based on measurement signals received from one or more position sensors 735. The one or more position sensors 735 may be an embodiment of the sensor device 115. A position sensor 735 generates one or more measurement signals in response to motion of the eyewear device 705. Examples of position sensors 735 include: one or more accelerometers, one or more gyroscopes, one or more magnetometers, another suitable type of sensor that detects motion, a type of sensor used for error correction of the IMU 745, or some combination thereof. The position sensors 735 may be located external to the IMU 745, internal to the IMU 745, or some combination thereof.

Based on the one or more measurement signals from one or more position sensors 735, the IMU 745 generates data indicating an estimated current position of the eyewear device 705 relative to an initial position of the eyewear device 705. For example, the position sensors 735 include multiple accelerometers to measure translational motion (forward/back, up/down, left/right) and multiple gyroscopes to measure rotational motion (e.g., pitch, yaw, and roll). In some embodiments, the IMU 745 rapidly samples the measurement signals and calculates the estimated current position of the eyewear device 705 from the sampled data. For example, the IMU 745 integrates the measurement signals received from the accelerometers over time to estimate a velocity vector and integrates the velocity vector over time to determine an estimated current position of a reference point on the eyewear device 705. Alternatively, the IMU 745 provides the sampled measurement signals to the console 715, which interprets the data to reduce error. The reference point is a point that may be used to describe the position of the eyewear device 705. The reference point may generally be defined as a point in space or a position related to the eyewear device's 705 orientation and position.

The IMU 745 receives one or more parameters from the console 715. As further discussed below, the one or more parameters are used to maintain tracking of the eyewear device 705. Based on a received parameter, the IMU 745 may adjust one or more IMU parameters (e.g., sample rate). In some embodiments, data from the DCA 740 causes the IMU 745 to update an initial position of the reference point so it corresponds to a next position of the reference point. Updating the initial position of the reference point as the next calibrated position of the reference point helps reduce accumulated error associated with the current position estimated by the IMU 745. The accumulated error, also referred to as drift error, causes the estimated position of the reference point to "drift" away from the actual position of the reference point over time. In some embodiments of the eyewear device 705, the IMU 745 may be a dedicated hardware component. In other embodiments, the IMU 745 may be a software component implemented in one or more processors.

The I/O interface 710 is a device that allows a user to send action requests and receive responses from the console 715.

An action request is a request to perform a particular action. For example, an action request may be an instruction to start or end capture of image or video data, start or end the audio system 720 from producing sounds, start or end a calibration process of the eyewear device 705, or an instruction to perform a particular action within an application. The I/O interface 710 may include one or more input devices. Example input devices include: a keyboard, a mouse, a game controller, or any other suitable device for receiving action requests and communicating the action requests to the console 715. An action request received by the I/O interface 710 is communicated to the console 715, which performs an action corresponding to the action request. In some embodiments, the I/O interface 715 includes an IMU 745, as further described above, that captures calibration data indicating an estimated position of the I/O interface 710 relative to an initial position of the I/O interface 710. In some embodiments, the I/O interface 710 may provide haptic feedback to the user in accordance with instructions received from the console 715. For example, haptic feedback is provided when an action request is received, or the console 715 communicates instructions to the I/O interface 710 causing the I/O interface 710 to generate haptic feedback when the console 715 performs an action.

The console 715 provides content to the eyewear device 705 for processing in accordance with information received from one or more of: the eyewear device 705 and the I/O interface 710. In the example shown in FIG. 7, the console 715 includes a tracking module 750, an engine 755, and an application store 760. Some embodiments of the console 715 have different modules or components than those described in conjunction with FIG. 7. Similarly, the functions further described below may be distributed among components of the console 715 in a different manner than described in conjunction with FIG. 7.

The application store 760 stores one or more applications for execution by the console 715. An application is a group of instructions, that when executed by a processor, generates content for presentation to the user. Content generated by an application may be in response to inputs received from the user via movement of the eyewear device 705 or the I/O interface 710. Examples of applications include: gaming applications, conferencing applications, video playback applications, calibration processes, or other suitable applications.

The tracking module 750 calibrates the system environment 700 using one or more calibration parameters and may adjust one or more calibration parameters to reduce error in determination of the position of the eyewear device 705 or of the I/O interface 710. Calibration performed by the tracking module 750 also accounts for information received from the IMU 745 in the eyewear device 705 and/or an IMU 745 included in the I/O interface 710. Additionally, if tracking of the eyewear device 705 is lost, the tracking module 750 may re-calibrate some or all of the system environment 700.

The tracking module 750 tracks movements of the eyewear device 705 or of the I/O interface 710 using information from the one or more sensor devices 735, the IMU 745, or some combination thereof. For example, the tracking module 750 determines a position of a reference point of the eyewear device 705 in a mapping of a local area based on information from the eyewear device 705. The tracking module 750 may also determine positions of the reference point of the eyewear device 705 or a reference point of the I/O interface 710 using data indicating a position of the eyewear device 705 from the IMU 745 or using data

indicating a position of the I/O interface 710 from an IMU 745 included in the I/O interface 710, respectively. Additionally, in some embodiments, the tracking module 750 may use portions of data indicating a position or the eyewear device 705 from the IMU 745 to predict a future location of the eyewear device 705. The tracking module 750 provides the estimated or predicted future position of the eyewear device 705 or the I/O interface 710 to the engine 755.

The engine 755 also executes applications within the system environment 700 and receives position information, acceleration information, velocity information, predicted future positions, audio information, or some combination thereof of the eyewear device 705 from the tracking module 750. Based on the received information, the engine 755 determines content to provide to the eyewear device 705 for presentation to the user. For example, if the received information indicates that the user has looked to the left, the engine 755 generates content for the eyewear device 705 that mirrors the user's movement in a virtual environment or in an environment augmenting the local area with additional content. Additionally, the engine 755 performs an action within an application executing on the console 715 in response to an action request received from the I/O interface 710 and provides feedback to the user that the action was performed. The provided feedback may be visual or audible feedback via the eyewear device 705 or haptic feedback via the I/O interface 710.

Additional Configuration Information

The foregoing description of the embodiments of the disclosure have been presented for the purpose of illustration; it is not intended to be exhaustive or to limit the disclosure to the precise forms disclosed. Persons skilled in the relevant art can appreciate that many modifications and variations are possible in light of the above disclosure.

Some portions of this description describe the embodiments of the disclosure in terms of algorithms and symbolic representations of operations on information. These algorithmic descriptions and representations are commonly used by those skilled in the data processing arts to convey the substance of their work effectively to others skilled in the art. These operations, while described functionally, computationally, or logically, are understood to be implemented by computer programs or equivalent electrical circuits, microcode, or the like. Furthermore, it has also proven convenient at times, to refer to these arrangements of operations as modules, without loss of generality. The described operations and their associated modules may be embodied in software, firmware, hardware, or any combinations thereof.

Any of the steps, operations, or processes described herein may be performed or implemented with one or more hardware or software modules, alone or in combination with other devices. In one embodiment, a software module is implemented with a computer program product comprising a computer-readable medium containing computer program code, which can be executed by a computer processor for performing any or all of the steps, operations, or processes described.

Embodiments of the disclosure may also relate to an apparatus for performing the operations herein. This apparatus may be specially constructed for the required purposes, and/or it may comprise a general-purpose computing device selectively activated or reconfigured by a computer program stored in the computer. Such a computer program may be stored in a non-transitory, tangible computer readable storage medium, or any type of media suitable for storing electronic instructions, which may be coupled to a computer system bus. Furthermore, any computing systems referred to

in the specification may include a single processor or may be architectures employing multiple processor designs for increased computing capability.

Embodiments of the disclosure may also relate to a product that is produced by a computing process described herein. Such a product may comprise information resulting from a computing process, where the information is stored on a non-transitory, tangible computer readable storage medium and may include any embodiment of a computer program product or other data combination described herein.

Finally, the language used in the specification has been principally selected for readability and instructional purposes, and it may not have been selected to delineate or circumscribe the inventive subject matter. It is therefore intended that the scope of the disclosure be limited not by this detailed description, but rather by any claims that issue on an application based hereon. Accordingly, the disclosure of the embodiments is intended to be illustrative, but not limiting, of the scope of the disclosure, which is set forth in the following claims.

What is claimed is:

1. A method comprising:
obtaining an array transfer function (ATF) for a plurality of combinations of acoustic sensors of a microphone array;

computing Euclidean norms of each obtained ATF over a target source range and a target frequency range;

computing an average of the Euclidean norms over the target source range and the target frequency range for each obtained ATF;

ranking each computed average; and
selecting a combination of acoustic sensors for the microphone array based in part on the ranking.

2. The method of claim 1, wherein each combination of acoustic sensors corresponds to a different arrangement of the acoustic sensors in the microphone array.

3. The method of claim 1, wherein each combination of acoustic sensors is a subset of the acoustic sensors of the microphone array.

4. The method of claim 1, wherein at least some of the acoustic sensors of the microphone array are coupled to a near-eye display (NED).

5. The method of claim 4, further comprising:
activating the selected combination of acoustic sensors.

6. The method of claim 5, wherein activating the selected combination of acoustic sensors comprises:

deactivating all of the other acoustic sensors in the microphone array.

7. The method of claim 1, further comprising:
estimating a direction of arrival (DoA) of a sound detected by one of the plurality of combinations of acoustic sensors relative to a position of the microphone array within the local area; and
selecting the target source range and the target frequency range based on the DoA estimation.

8. The method of claim 1, further comprising:
detecting a sound by one of the plurality of combinations of acoustic sensors;

estimating a direction of arrival (DoA) of the detected sound relative to a position of the microphone array within the local area.

9. The method of claim 8, further comprising:
refining the DoA estimation using data from the selected combination of acoustic sensors.

25

10. The method of claim 9, further comprising: generating, based on the refined DoA estimation, a head-related transfer function (HRTF) for the position of the microphone array in the local area.
11. The method of claim 10, further comprising: providing audio content customized to the user based in part on the HRTF.
12. The method of claim 8, further comprising: detecting a second sound by the selected combination of acoustic sensors; estimating a second DoA of the second detected sound relative to a second position of the microphone array within the local area; determining that the second detected sound has an associated parameter that is within a threshold value of a target parameter; and updating a pre-existing HRTF based on the second DoA estimation, the pre-existing HRTF associated with the second position of the microphone array within the local area.
13. The method of claim 12, wherein the parameter describes a feature of the detected sound, the feature selected from a group consisting of: frequency, amplitude, duration, and DoA.
14. The method of claim 8, further comprising: detecting a second sound by the selected combination of acoustic sensors; estimating a second DoA of the second detected sound relative to a second position of the microphone array within the local area; determining that the second detected sound has an associated parameter that is within a threshold value of a target parameter; and generating a second HRTF based on the second DoA estimation, the second HRTF associated with the second position of the microphone array within the local area.
15. An audio system comprising: a microphone array that includes a plurality of acoustic sensors that are configured to monitor sounds in a local area surrounding the microphone array, and at least some of the plurality of acoustic sensors are coupled to a near-eye display (NED); a controller configured to: obtain an array transfer function (ATF) for a plurality of combinations of acoustic sensors of the microphone array;

26

- compute Euclidean norms of each obtained ATF over a target source range and a target frequency range; compute an average of the Euclidean norms over the target source range and the target frequency range for each obtained ATF; rank each computed average; and select a combination of acoustic sensors for the microphone array based in part on the ranking; and activate the selected combination of acoustic sensors.
16. The method of claim 15, wherein the controller is further configured to: detect a sound by one of the plurality of combinations of acoustic sensors; estimate a direction of arrival (DoA) of the detected sound relative to a position of the microphone array within the local area.
17. The audio system of claim 16, wherein the controller is further configured to: refine the DoA estimation using data from the selected combination of acoustic sensors.
18. The audio system of claim 17, wherein the controller is further configured to: generate, based on the refined DoA estimation, a head-related transfer function (HRTF) for the position of the NED in the local area.
19. The audio system of claim 18, wherein the controller is further configured to: provide audio content customized to the user based in part on the HRTF.
20. A non-transitory computer-readable medium storing instructions that, when executed by one or more processors, cause the one or more processors to perform operations comprising: obtaining an array transfer function (ATF) for a plurality of combinations of acoustic sensors of a microphone array; computing Euclidean norms of each obtained ATF over a target source range and a target frequency range; computing an average of the Euclidean norms over the target source range and the target frequency range for each obtained ATF; ranking each computed average; and selecting a combination of acoustic sensors for the microphone array based in part on the ranking.
